UNITED STATES PATENT OFFICE.

CHRISTIAN AALBORG, OF PITTSBURGH, PENNSYLVANIA, ASSIGNOR TO WESTINGHOUSE ELECTRIC & MANUFACTURING COMPANY, A CORPORATION OF PENNSYLVANIA.

SNAP SWITCH.

Application filed August 30, 1920. Serial No. 406,844.

To all whom it may concern:

Be it known that I, CHRISTIAN AALBORG, a citizen of the United States, and a resident of Pittsburgh, in the county of Allegheny and State of Pennsylvania, have invented a new and useful Improvement in Snap Switches, of which the following is a specification.

My invention relates to electric snap switches, and it has for its object the provision of a switch having means for positively imparting movements to the blades without losing any of the desirable features of the ordinary "snap" action.

One form of mechanism for accomplishing this result is shown in the accompanying drawing wherein—

Fig. 1 is a plan view of the switch in closed position.

Fig. 2 is a side elevation showing, in full lines, the parts in closed position, and, in dotted lines, the position occupied by the movable parts when the switch is open.

Fig. 3 is an elevation taken at right angles to the view of Fig. 2, and

Figs. 4, 5 and 6 are views similar to those of Figs. 1, 2 and 3, showing the application of the invention to a switch of the oscillating type.

As shown in Fig. 1, the construction includes the usual switch blades 4, pivoted at 5, and having frictional engagement with contacts 6. The outer ends of the blades carry the cross bar 7 which is made of a non-conducting material.

A link 8 (Fig. 2) is pivoted to the cross bar 7, at the point 9, while, at point 10, this link has a pivotal connection with the lever 11. At its lower end, the lever 11 is pivoted, at 12, to the frame 13 and is provided, at its upper end, with a bent-over portion 14 and, at its lower end, with spaced lugs 14a and 14b.

Pivoted to the frame 13, at 15, is the handle 16 which carries, at its lower end, an outstanding lug 17 supporting one end of the spring 18 and so positioned as to abut against one of the lugs 14a and 14b when the handle is moved to "on" or to "off" position. The other end of the spring 18 is connected to the pivot 10.

By reference to Fig. 2, it will be seen that the spring 18, by reason of its connection to the handle 16 and the pivot 10, serves to hold the blades 4 in either open or closed

position—depending upon whether the handle is in its on or its off position.

Starting with the switch in closed position, the handle 16, when moved to the left, brings its lugs 17 to bear against the lug 14a, thus imparting positive movement to the blades 4 for a distance sufficient to move them out of frictional engagement with the contacts 6. During this movement of the handle 16, the spring 18 is placed under increased tension, and the angle of pull on the pivot 10 is moved to the right sufficiently far to cause the blades to be thrown to the position indicated in dotted lines. When it is desired to close the switch, a movement of the handle in the opposite direction causes a reversal of the action just described.

In Figs. 4, 5 and 6 is shown a switch of the oscillating type. In this construction, blades 19, connected by a cross head 20, oscillate about pivots 21 carried in projecting lips 22 of a frame 23, and, at their opposite ends, frictionally engage contacts 24 and 25, respectively.

Riveted to the cross head 20 is an arm 26 having pivotal connection to one end of a link 27 which, at its other end, is pivotally connected to a lever 28 and to one end of a coil spring 29. The other end of the coil spring is secured to an outstanding lug 30 on a handle 31 pivoted at 32 to the frame 23.

When the handle 31 is moved to its "on" or to its "off" position, the lug 30 abuts against shoulders 33 or 34 respectively, carried on the lower end of the lever 28, causing such lever to rock on its pivot 35.

The operation of the mechanism just described is substantially the same as the device of Figs. 1 to 3, except that, due to the blades being pivoted intermediate their ends, the addition of the link member 27 is necessary in order to impart oscillatory movement to the blades 19 as the handle is moved back and forth.

My invention is not limited to the specific structure illustrated, as it may be variously modified without departing from the spirit and scope of the invention, as set forth in the appended claims.

I claim as my invention:

1. In an electric switch, the combination with a base, a stationary contact member, and a movable contact member pivotally supported from the base, of an outwardly extending arm carried by the movable contact.

member, a handle pivotally supported at a point remote from the base and provided with an arm extending inwardly past the first mentioned arm, a resilient connection between the remote ends of the respective arms, and a pair of spaced stop shoulders connected to the movable contact member and engaged and actuated by the handle for imparting positive movement to the movable contact member in either direction during a portion of its movement.

2. In an electric switch, the combination with a base, an operating lever and a bridging member pivotally supported by the base, a link mechanism pivotally connected to the bridging member and extending to a point intermediate the ends of the operating lever, and a yielding connection between the link mechanism and the operating lever, the connection of the yielding element to the link mechanism being at a point remote from the base and the connection of the said element to the operating lever being at a point adjacent to the base.

3. In an electric switch, the combination with a pivotally supported operating handle and a pivotally supported bridging member, of a projection carried by the handle, a projection carried by the bridging member and extending past a portion of the first named projection, a yielding element interposed between the said projections and having engagement therewith, and a pair of spaced shoulders connected to the bridging member and actuated by the projection on the handle for imparting positive movement to the bridging member after a predetermined movement of the handle, the engagement of the yielding element with the projection of the bridging member being at a point adjacent the point of pivotal support for the handle and its engagement with the operating handle being at a point remote from the said pivotal support.

In testimony whereof, I have hereunto subscribed my name this 4th day of August, 1920.

CHRISTIAN AALBORG.
